LOCK MECHANISM

Arthur G. Lyons, Pennside, Pa., assignor to
Reading Hardware Corporation, Reading, Pa.,
a corporation

Application March 3, 1932, Serial No. 596,621

1 Claim. (Cl. 70—29)

This invention relates to improvements in lock mechanisms.

The primary object of this invention is the provision of an improved lock mechanism for guest room corridor doors having a dead bolt and a latch bolt, both of which may be operated by an emergency key from the corridor; the floor-maid's key and guest key being constructed so that they may only actuate the latch bolt when the dead bolt is retracted.

Other objects and advantages of this invention will be apparent during the course of the following detailed description.

In the accompanying drawings, forming a part of this specification, and wherein similar reference characters designate corresponding parts throughout the several views,

Figure 1 is a fragmentary view, partly in section, showing the lock mechanism with both the dead and latch bolts in locking positions, and showing that the guest key and floor-maid's key under such circumstances are inoperative to retract either of the bolts from the corridor side of the door.

Figure 2 is a view showing the lock parts of Figure 1, but with the bolts retracted, and showing the manner in which the throw-back of the lock may actuate the latch bolt to retract the same.

Figures 3 and 4 are cross sectional views taken respectively on their respective lines in Figures 1 and 3 of the drawings.

Figure 5 is a view of the details of the improved lock showing the latch bolt extended and a portion of the emergency key in the cylinder lock and in position to start the projection of the dead bolt.

Figure 6 is a perspective view of the key actuated plug of the cylinder lock.

Figure 7 is a sectional view similar to Figure 4, but showing the emergency key in the plug of the cylinder lock.

Figure 8 shows the type of key which is in the possession of the floor-maid and guest.

Figure 9 shows the emergency key.

In the drawings, wherein for the purpose of illustration is shown only a preferred embodiment of the invention, the letter A may generally designate the improved lock mechanism, which may include a case B of any approved nature, having a dead bolt mechanism C and a latch bolt mechanism D associated therewith. A pin tumbler cylinder lock E of improved construction is provided for actuating the bolts C and D; being

actuated to this end by means of an emergency key F and a guest and maid's key G.

The lock case B may include a face plate 10, opposite side walls 15 and 16, and marginal boundary walls 17. Of course the structural features and nature of the case B may vary widely, although in the main it will be of the mortise type.

The dead bolt mechanism C includes a reciprocating frame 20 mounted in the lock case, and having the dead bolt proper 21 affixed therewith. Suitable means are of course provided in the case to guide the movement of the frame 20. A tumbler 22 is pivotally carried at 23 by the dead bolt frame 20, being spring urged at 24 so that its cam engaging shelf 25^a is in normal position to be engaged by the cam 25 of the cylinder lock E. A fence 27 is carried by the case B against which a portion 28 of the tumbler 22 engages to lock the dead bolt 21 in retracted or projected position, as is shown in Figures 1 and 2 of the drawings. A spring actuated lever 30 is pivoted on the dead bolt frame 20, the same having a heel 31 which forms the forward part of the cam engaging throat of the lock; the bolt frame 20 itself having a rear heel 32. These parts are more particularly described in Patent #1,678,994, July 31, 1928, and their operation will be well understood.

Since in this lock mechanism both the dead bolt and latch bolt are adapted to be actuated by the cam or roll back 25, the latch mechanism is substantially the same as that set forth in the patent above mentioned. The latch bolt mechanism D includes the latch bolt proper 35 upon the fore end of a slidable stem or frame 36; a spring 37 normally actuating the latch bolt proper 35 into a "shot" position. The latch bolt mechanism further includes a lever 38 pivoted at 39 upon the dead bolt frame 20, and engageable at its free end with a shoulder or cross head 40 on the frame of the latch bolt mechanism. This lever has a lug 42 near its pivoted end engageable by a movable end of a cam actuated lever 44, which is pivoted on the dead bolt frame at 45.

If desired, the tumbler 22 may be of a type actuated by a thumb piece at the inside of the door, under control of the guest, in order to throw the bolt mechanism without the use of the key. However, in the drawings the dead and latch bolts are shown as solely actuated by the keys.

The operation of the dead and latch bolts will be understood from the foregoing. If both the dead and latch bolts are projected in locking position, as shown in Figure 1, it will be necessary to throw the cam 25 from the position shown in

Figure 1 to the position shown in Figure 2 for complete retraction of both the dead and latch bolts. This movement of the cam 25 takes place through substantially one complete turn of the cylinder lock plug, as can well be understood. Of course the dead bolt is retracted first, and subsequently when the dead bolt frame has been moved to position the cam engaging end of the lever 44 in the path of the cam 25 the said lever 10 44 is depressed, as shown in Figure 2, to retract the latch bolt.

With the general features of the bolt mechanism as above described it is the principal object of this invention to enable either the guest or maid from the corridor side of the door to throw the cam 25 in order to retract the latch bolt when the dead bolt is retracted. This is effected by limiting the angular movement of the cam 25, sufficient only to retract the latch bolt proper 20 35 when the dead bolt proper 21 is in a retracted position.

Referring to features of the cylinder lock E the same includes a cylindrical shaped casing 50 which is externally screw threaded for connection in the walls 15 or 16 of the case B in usual manner. This casing 50 is provided with an eccentric circular bore 51 therethrough within which the usual cylindrical shaped plug 52 is rotatably mounted. The plug 52 is provided at its outer end with the annular flange 53 which seats in a countersunk relation in the face of the casing 50, as shown in Figure 3. The end of the plug 52 which projects beyond the inner end of the casing 50 is provided with a diametrically disposed shank 55 which fits into the slotted end of the cam 25; the latter being held in place upon the inner end of the plug 52 by means of screws 56 which detachably connect in suitable screw threaded openings 57 on the inner end of the plug. 35 40 45 This arrangement assembles the plug in place in the cylinder casing 50. The plug 52 is provided with the key shank receiving slot 60 therealong, and conventional pin tumbler mechanism 62 is provided in proper association with the casing 50 and plug 52 in order to control rotation of the plug 52, and consequently angular movement of the cam 25.

The plug 52 adjacent to its outer end is provided with an annular groove 65. The casing 50 is provided with oppositely disposed members 66 and 67, which in the form of invention illustrated are screws, threaded for detachable seating in screw threaded passageways 68 and 69 respectively provided in the casing 50. These screws when properly seated in their openings 68 and 69 have the kerfed head ends thereof disposed inwardly of the outer surface of the casing 50. Their inner ends are respectively provided with semispherical projections 70 and 71 which are in position to extend into the bore 51 of the casing 50, and more particularly into the groove 65 of the plug 52 so as to interpose obstructions to an ordinary key inserted into the key slot 60.

65 The key F includes a shank 70 having the upper edge 71 thereof provided with indentations 72 into which the pin tumblers of the cylinder lock 50 fit in a relation which will enable the plug 52 to be rotated by the key F, in a manner 70 which is perfectly apparent. It will be noted that the shank 70, as the key is slid into place, intersects the annular groove 65 of the plug 52. For the key F the opposite edge 73 is provided with a notch or indentation 74 which, when the key 75 is fully in place in the cylinder lock lies flush

with the groove 65 so that as the plug 52 is rotated by the key F the key shank will not prove to be an obstruction against the ends 70 and 71 of the pins 66 and 67. Thus with the key F one is able to complete the rotation of the plug 52 for operating the cam 25 of the cylinder lock against the tumbler 22 of the dead bolt mechanism C, and also against the operating lever 44 of the latch bolt mechanism D, so that the dead bolt and latch bolt may be projected or retracted by the key F.

The key G is of identically the same construction as the key F except for the fact that no notch is provided inwardly of the rear edge 73^a thereof. Thus, during rotation of the plug 52, 80 90 with the key G in the slot, the back of the shank of the key G will hit against the projecting ends 70 and 71 of the cylinder lock pins 66 and 67, limiting the angularity of movement of the plug 52 so that it will be totally impossible to operate 95 the tumbler 42, as is clearly shown in Figure 1 of the drawings. In fact the latch bolt D may only be operated when the dead bolt C is retracted, since then the operating end of the lever 44 will lie in position to be engaged by the 100 cam 25 at a time immediately prior to the time that the shank of the key G hits against the pin end 71, as can be understood from Figures 1 and 2 of the drawings. This interposition of the shank of the key G across the groove 65 is well 105 shown in Figure 4 of the drawings, and in contradistinction the alignment of the notch 74 with the groove 65 is shown in Figure 7 of the drawings.

It is to be understood that the maid's key and the guest key are identically the same as shown for the key G in Figure 8 of the drawings. The corridor side of the door would have a rigid knob so that there would be no lock operation by means of the knob. If the guest is out of his 110 115 or her room it is quite apparent that the dead bolt will be retracted and of course the floor-maid with her key G may enter the room because in this position of the lock the dead bolt is retracted and the latch bolt parts are in position 120 to be operated and retracted by means of the maid's key. When the guest enters from the corridor side of his door to his room, and for additional security throws the dead bolt, either by means of a turn knob (not shown in the drawings) of well known construction, or by means 125 of a cylinder lock of a type which does not employ the stop screws 66 and 67, it is quite apparent that the floor-maid cannot unlock the door, and thus the guest is assured of privacy. 130 The emergency key F is of course under control of the manager or owner of the hotel who can at all times unlock the guest's door. This is sometimes necessary in event the guest becomes ill in his or her room and is unable to arise in 135 order to unlock the door. The key F can also be used by the management in order to lock the door from the corridor side, thus preventing the guest from entering his or her room without consulting the manager.

Various changes in the shape, size, and arrangement of parts may be made to the form of invention herein shown and described, without departing from the spirit of the invention or the scope of the claim.

I claim:

The combination with a mortise lock mechanism having a latch bolt and an operating member therefor, a dead bolt and an operating member therefor, a cylinder lock including a casing, a rotary plug mounted in the casing having a 150

lock operating cam for engaging with said operating members, pin tumbler means normally in position to lock said plug against rotation in said casing, said plug having a key slot therein 5 for receiving the shanks of master and other keys, said plug having a continuous groove thereabout, a stop projection fixed on the casing of the cylinder and projecting into said groove so as to lie directly in the path of a predetermined 10 type of key other than the master key to limit the angular rotary movement of the plug in the casing, said stop projection being so positioned relative to the operating member of the latch bolt that when such predetermined type of key is inserted in the cylinder lock and turned the lock operating cam will actuate merely said latch bolt operating member and be prevented from actuating the dead bolt operating member by means of engagement of the shank of such predetermined key with said stop pin, the plug being operable by a master key which is notched in the plane of said plug groove so that upon turning of said master key the plug cam may 15 actuate both of said actuating members.
